SAFETY MEANS FOR TANKS

Robert W. Crossen, Jr., Plainfield, Ill., assignor to
Farrell Manufacturing Company, Joliet, Ill., a
corporation of Illinois

Application July 30, 1932, Serial No. 626,434

10 Claims. (Cl. 137—162)

This invention pertains to tanks and tank trucks, and more particularly to safety means for controlling the discharge valves from said tanks.

5 In some forms of tanks, particularly tank trucks or cars for dispensing gasoline to service stations and the like, it is not unusual for the truck to contain a plurality of different combustible substances such as gasoline, fuel oil 10 and the like, disposed in a plurality of separate tanks, each controlled by a separate control valve operated from one source. The control valves are also adapted to be individually operated for convenience or safety. The ordinary 15 single control is generally placed at the after end of the tank with an auxiliary control adjacent the forward end of the tank so that the valves may be shut from either station. In the event that fire occurs, it usually occurs adjacent the after end of the tank where the discharge faucets are located and it therefore may 20 be impossible for the operator to close the valves from the main control.

It is therefore an object of this invention to 25 provide means associated with the individual valves of a tank for controlling said valves for emergency operation.

Another object is to provide a fusible link connection for automatic emergency control of the 30 discharge means of a combustible fluid dispensing container.

With these and various other objects in view, the invention may consist of certain novel features of construction and operation as will be 35 more fully described and particularly pointed out in the specification, drawings and claims appended hereto.

In the drawings, which illustrate an embodiment 40 of the device and wherein like reference characters are used to designate like parts—

Figure 1 is a top plan view of a tank provided with the emergency control means showing the invention applied for the control of separate valves;

45 Figure 2 is an end elevation of the tank construction shown in Figure 1;

Figure 3 is an enlarged top plan view of the control valve operating means;

Figure 4 is a sectional elevation taken substantially in the plane as indicated by line 4—4 of Figure 3;

Figure 5 is an enlarged end elevation of the fusible link control mechanism;

55 Figure 6 is a side elevation of the fusible link control mechanism;

Figure 7 is a sectional elevation taken substantially in the plane as indicated by the line 7—7 of Figure 5.

In the application of the invention to a tank, a form is shown applicable to a tank truck 5 wherein the tank 10 is provided with a number of compartments therein to which ingress may be had through the manholes 12. Each of said compartments is adapted to be drained or have liquid dispensed therefrom through a 10 suitable bottom valve (not shown) controlled by the control valve mechanism 14. The control valve mechanism includes the rotating cam or cap 16 secured to the valve control rod 18, the rod passing through the cap and being provided with the operating lever 20. The rod 18, together with the cam 16, gravitally seats upon the annular portion 11 of the tank 10 as shown in Figure 4. Rotation of the cam member 16 by the lever 20 will produce vertical movement 15 of the rod 18 and actuate the valve at the lower end of the rod 18. The lever 20 is notched as 20 at 22 for the reception of the individual operating handle 24, the handle being pivoted as at 26 to the support 28 provided on the cap 16 and 25 normally urged to engagement with the notch by means of the spring 30.

Each lever 20 is pivoted to a drag link 32, which in turn is pivoted to the lever 34 provided on the operating rod 36, the operating rod being journaled on the tank 10 in the supports 38. The end of the operating rod 36 adjacent the rear of the tank is provided with the lever 40 which is pivotally mounted between the spaced arms or bifurcated portions 42 of the fusible link mechanism 35 44. The fusible link mechanism 44 includes the casing 46 integral with the arms 42, the casing being open adjacent one end for the reception of the rod 48. The rod 48 extends into the casing and is provided with the washer 50 secured to said 40 rod, between which washer and the shoulders 52 the spring 54 is provided. The casing 46 is notched as at 56 for the reception of the legs of the spring 58. The legs of the spring 58 maintain the washer in position to compress the spring 54 between the shoulders 52 and the washer 50. The spring 58 is retained in operative position by means of the fusible link 60 secured as at 62 between the legs of the spring 58. The rod 48 is 45 pivoted to the lever 64 provided on the control shaft 66, the control shaft being operated by the operating handle 68.

For emergency operation, the shaft 36 is provided with the arm 70 spring pressed as at 72 to 50 55

turn the shaft 36 in a clockwise direction as viewed in Figure 2, the arm being connected to the chain control 74 passing through the conduit or casing 76 to the operating handle 18 disposed adjacent the forward end of the tank. In order to operate the valves it is only necessary to operate the handle 68 in a clockwise direction as viewed in Figure 1, causing rotation of the lever 20 to rotate the entire cap 16 of each of the valves. In 10 the event it is desired to disengage any one of the valves, it is only necessary to revolve the handle 24 out of the notch 22, in which case the remaining valves can be operated from the handle 68, or the individual valve can be operated through its handle 24.

In event of fire or other hazard adjacent the rear end of the tank, in which case it would be impossible for an operator to reach the station at the handle 68, the valves might be simultaneously 20 operated through the emergency handle 78. However, the fire adjacent the end of the tank would melt the fusible link 68, causing the legs of the spring 58 to be disengaged from the notches 56 of the casing 46, releasing the washer 59. The 25 spring 54 will cause the casing 46 to move toward the left as viewed in Figure 7, to thereby rotate the levers 20 in a counter-clockwise direction as viewed in Figure 1, and thereby shut the valves. In this case the source of supply to the discharge 30 faucets will be cut off, and the fire hazard greatly lessened.

It is to be understood that I do not wish to be limited by the exact embodiment of the device shown, which is merely by way of illustration and 35 not limitation, as various and other forms of the device will of course be apparent to those skilled in the art without departing from the spirit of the invention or the scope of the claims.

I claim:

40 1. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank and connected to said levers for operation thereof, a handle for rotating said shaft, said levers and said cam members, and means outside of said tank for automatically rotating said shaft to operate said levers and said cam members.

45 2. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank and connected to said levers for operation thereof, a handle for rotating said shaft, and means between said handle and shaft for automatically rotating said shaft to operate said levers and said cam members.

50 3. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank and connected to said levers for operation thereof, a handle for rotating said shaft, and means for automatically rotating said shaft to operate said levers and said cam members, said

means including a housing, a rod extending into said housing and provided with a shoulder, a longitudinally expansible spring disposed between said shoulder and said housing, a second laterally expansible spring disposed between said shoulder and housing and normally rendering said first named spring inoperative, and a fusible link for controlling said second named spring, whereby fusing of said link permits lateral expansion of said second spring which, in turn, releases the 10 first-named spring for rotation of said shaft and operation of said levers and said cam members.

4. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank and connected to said levers for operation thereof, a handle for rotating said shaft, means for automatically rotating said shaft to operate said levers and said cam members, said means including a housing, a rod extending into said housing and provided with a shoulder, a longitudinally expansible spring disposed between said shoulder and said housing, a second laterally expansible spring disposed between said shoulder and housing and normally rendering said first named spring inoperative, and releasable means 20 cooperating with said second named spring and arranged so that release of said means disengages said second named spring by lateral movement from said shoulder to permit relative longitudinal movement between said housing and rod.

5. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank and connected to said levers for operation thereof, a handle for rotating said shaft, and means for automatically rotating said shaft to 45 operate said levers and said cam members, said means including a spring releasable for operative reaction between said handle and said shaft.

6. In a tank, the combination of a plurality of compartments, valve control means for controlling discharge from said compartments, said control means including a cam member for each compartment, a lever for each cam member for operating said cam members, a rotatable shaft mounted on and extending longitudinally of the tank 55 and connected to said levers for operation thereof, a handle for rotating said shaft, and means for automatically rotating said shaft to operate said levers and said cam members, said means including a spring releasable for operative reaction between said handle and said shaft and a fusible link for releasing said spring.

7. In a fuel tank having a plurality of fuel compartments, emergency discharge control means for each compartment, manually operable means for simultaneously operating the discharge control means for each compartment, said last-named means including a fusible link through which movement may be normally transmitted 70 and said fusible link including expansible means releasable upon fusing of said link for operating said discharge control means automatically.

8. In a fuel tank having a plurality of fuel compartments, emergency discharge control means 75

for each tank, manually operable means for individually operating said discharge control means, manually operable means for simultaneously operating the discharge control means for each compartment, said last-named means including a fusible link through which movement may be normally transmitted and said fusible link including expansible means releasable upon fusing of said link for operating the discharge control means for each compartment automatically.

9. In a fuel tank having a plurality of fuel compartments, emergency discharge control means for each compartment mounted on the top portion of said tank including a rotatable cam member, means for individually operating said cam members and means adjacent one end of said

tank for simultaneously operating all of said cam members.

10. In combination with a fuel tank having a plurality of fuel compartments, valve control means for controlling the discharge from each of said compartments including a rotatable cam member at the top of each of said compartments and lever arms for operating each cam member, means for individually operating said cam members, a rotatable operating shaft mounted on said tank and extending longitudinally thereof, operative connections between said shaft and each of said lever arms and independently operable means for rotating said shaft from either end thereof.
